UNITED STATES PATENT OFFICE.

WILLIAM A. HARRIS, OF BOSTON, MASSACHUSETTS, ASSIGNOR TO THE FLINTKOTE COMPANY, OF BOSTON, MASSACHUSETTS, A CORPORATION OF MASSACHUSETTS.

ROOFING SHINGLE.

Application filed February 27, 1925. Serial No. 11,968.

This invention relates to flexible prepared roofing shingles such as are prepared from a flexible sheet comprising a fibrous foundation of rag or asbestos felt, saturated with asphalt or other waterproof bituminous composition, 5 coated with a layer of relatively high melting point asphalt, e. g. blown asphalt, and surfaced with a layer of partially embedded crushed slate or other grit.

10 The object of the present invention is to produce such shingles in a form by which a maximum area of roof surface may be covered by shingles requiring a minimum area of material; by which the lower or exposed portions 15 of the shingles may be interlocked with laterally adjacent shingles in any one of a plurality of ways to produce different patterns on the roof, certain of such ways resulting in larger and smaller overlapping areas; 20 by which said shingles may be accurately placed and spaced apart on the roof or other surface to be covered; by which such shingles may be produced from the initial sheet of roofing material substantially without any 25 waste; and by which other advantages are attained as will subsequently be pointed out. On the accompanying drawings:

Figure 1 represents how the shingles may be cut or formed from a sheet of roofing material.

30 Figure 2 represents one of the shingles.

Figure 3 illustrates the appearance of the shingles when laid and interlocked on a roof by a method giving the larger overlapping area.

35 Figure 4 illustrates one of these shingles with its lower interlocking end underfolded.

Figure 5 illustrates one of the shingles with its lower interlocking end underfolded on its 40 transverse center line.

Figures 6 and 7 are edge views of the shingles of Figures 4 and 5 respectively.

Figure 8 shows the way in which the shingle shown in Figure 4 is laid.

45 Figure 9 illustrates the appearance of the shingle shown in Figure 5 when laid.

Figure 10 illustrates the appearance of the shingles interlocked on a roof by the method giving the smaller overlapping area.

50 Fig. 11 represents a shingle having holes in the ends of the lateral slots.

55 While shingles embodying the present invention may be placed on newly-built roof structures they are of especial value in covering previously shingled roofs.

Each shingle as shown in Figure 2 may be considered as having an upper portion 1 and a lower portion 2 which are of equal lengths, the upper portion being rectangular and the lower portion being approximately rectangular with the exception to be noted. The shingle has straight parallel upper and lower edges 3 and 4. The upper portion has parallel side edges 5, 5 and the lower portion has parallel side edges 6, 6 lying within and parallel to the upper side edges 5, 5. The width of the lower portion is thus less than that of the upper portion and there are shoulders 7, 7 and 9, 9 spaced from one another by preferably inclined and relatively short intermediate edges 60 8 between edges 5, 5 and 6, 6, which bound an intermediate small trapezoidal area between the upper and lower portions. The pair of shoulders 7 and 9 on each side of the shingle as shown are in stepped relation and 65 preferably in close juxtaposition so that they may together be accurately described as a double shoulder. The shoulders 7 and 9 may be parallel to edges 3 and 4, or either upwardly or downwardly inclined. The transverse 70 median line of the shingle corresponds to the transverse median line of the intermediate area. Extending laterally from the extremity of the lower portion 2 at its lower corners are two tabs 12, 12, formed by cutting notches 75 with the upper edges 10 thereof forming symmetrical angles with the lower edges 11, which, if desired, may be horizontal, though preferably upwardly and outwardly inclined. These tabs preferably are of a width equal 80 to the perpendicular distance between the shoulders 7 and 9, and are of a length equal 85 to the perpendicular distance between edges 5 and 6.

90 In producing the sheet of roofing material of the character hereinbefore described, the sheet is slit longitudinally into strips by a longitudinal cut $a-a$, as in Figure 1, so that each strip in width is equal to the length of an individual shingle. Each strip is cut transversely of its length on lines $b-b$ and $c-c$ alternately to form a side edge of the shingle, the lines of severance being such that the portions b^1c^1 , b^2c^2 divide each strip into shingles with the narrow part of one shingle 95 lying next to the wide part of the succeeding shingle. Notches are then cut in the shingles near the extremities of the narrow portions. By this method of forming the strips there 100 is substantially no waste material. Of course 105 110

the sheet may be slit either before or after it is cut transversely, or the slitting and the transverse cutting may be accomplished simultaneously.

5 The shingles are laid in courses with the narrow lower portions extending downwardly from the wider portions, as shown in Figure 3. They are widely spaced laterally so that in each course the lower portions 2, 2
10 of the two laterally adjacent shingles are separated by a space which may be equal to the narrow portion of a shingle, minus twice the lateral extension of the tabs 12, 12. When the first course is thus laid and secured in
15 place by nails or fasteners, as at 13, the next course is applied. In so doing, the lateral tabs 12, 12 of one shingle are inserted beneath the edges 6, 6 of two adjacent already laid shingles and the shingle being laid is
20 drawn upwardly until the upper edges 11, 11 of the tabs engage the shoulders 7, 7 of the previously laid shingles at the reentrant angles formed by the shoulders 7 and the side edges 6. In this way each shingle of one
25 course is interlocked at its lower end with the middle portion of two laterally adjacent shingles of the previously laid lower course. When several courses have been laid and the roof surface is completely covered, the lower
30 narrow portion of each shingle laterally overlaps the wide upper portion of two laterally adjacent shingles of the next lower course, and longitudinally overlaps the middle portion of an aligned shingle in the second lower
35 course.

In Figure 2 I have shown by the unshaded area the portion of the shingle which is exposed when it is laid, the remaining hatched area *d* and *e* being that which is overlapped and covered by adjacent shingles of the next
40 two higher courses. As a result of this construction, assuming that each shingle is 18 inches long, that the width of its upper portion is 17 inches, and the width of the lower portion 13 inches, then 100 square feet of area is covered by 168.7 square feet of roofing material formed into shingles as herein described. I may also lay the shingles as follows:—

50 The shingles are laid with narrow lower portions extending downwardly from the wider portions, as shown in Figure 10. They are widely spaced laterally so that in each course the lower portions are separated by a
55 space which may be equal to the narrow portion of the shingle minus twice the length of the shoulders 9. When the first course is thus laid and secured in place, the next course is applied. In so doing, the lateral tabs 12,
60 12 are inserted beneath the inclined inner edges 8, 8 of two adjacent already laid shingles, and the shingle is positioned so that the upper edges 11, 11 of the tabs 12, 12 engage the shoulders 9, 9 of the previously laid shingles at the reentrant angles formed by

the shoulders and the inclined edges 8. In this way each shingle of one course is interlocked at its lower end with the middle portion of two laterally adjacent shingles of the previously laid lower course to form a different pattern on the roof. After several courses have been laid and the roof surface is completely covered, the lower portion of each shingle laterally overlaps the wide upper portion of the two lateral adjacent shingles 75 of the next lower course and longitudinally overlaps the middle portion of an aligned shingle in the second lower course.

In Figure 2 I have shown by the shaded area *e* the entire portion of the upper end of 80 the shingle overlapped and covered by adjacent shingles in the next two higher courses by this method of laying. As a result of this construction, assuming that each shingle is of the dimensions previously stated, 100 85 square feet of roof surface is covered by approximately 145 square feet of roofing material formed with shingles as described.

I find it desirable in some cases to fold back and under the lower end of the shingle on the transverse line *d*, *d* (Figure 2), which is in alignment with the upper edges 11 of the lateral tabs 12 as shown in Figures 4 and 6. The flap or under folded portion 14 may be cemented to the under side of the shingle by asphalt or the like, as indicated in Figure 7. When the shingles, folded as shown in Figure 6, are laid, the laterally extending tabs engage the shoulders 7, 7 of the laterally adjacent shingles and form a pattern on the roof 100 slightly different from the others heretofore described, as shown in Figure 8. Or I may fold back and under the lower end of the shingle on the central transverse line *e*, *e* of the tabs, as shown in Figures 2, 5 and 7. 105 They may be laid in the same manner as the shingles shown in Figure 8; and the pattern formed on the roof as shown in Figure 9 is slightly different from that shown in Figure 8. The upper layer of the tab as folded 110 is then preferably cut away so that a single thickness only engages beneath the adjacent shingles. This under folding doubles the thickness of the butt ends of these shingles, presenting a more pleasing and substantial 115 appearance to the roof and makes a stiffening element which holds the shingles tighter against the roof surface.

In place of the slots to define the tabs 12, slits 15 extending inwardly from the shingle 120 edges to perforations 16 may be employed, as shown in Figure 11.

In any event, the shingles when laid form lateral courses of symmetrical figures which extend from the peak to the eaves of the roof. 125 Each shingle is secured by nails which are concealed and at its lower corners is interlocked with the shingles of the lower course. A maximum area of roof surface is covered and adequately protected against the weather 130

by shingles requiring a minimum quantity of material.

Inasmuch as the shingles are flexible, the laterally projecting tabs may easily be bent below the plane or body of the shingle to lie beneath the laterally adjacent shingles of the lower course.

What I claim is:

1. A flexible roofing shingle having parallel ends and parallel sides, the upper portion which is substantially one half the length of the shingle being wider than the lower portion, and defined therefrom by a pair of shoulders on each side parallel to the ends, one shoulder extending inwardly from the side edge of the upper portion to a short intermediate edge and the other shoulder extending inwardly from the intermediate edge to the side edge of the lower portion, and the lower portion having notches cut near its extremity to form tabs laterally extending a distance equal to the perpendicular distance between the side edges of the upper and lower portions.

2. A flexible roofing shingle having parallel ends and parallel sides, the upper portion which is substantially one half the length of the shingle being wider than the lower portion, and defined therefrom by a pair of shoulders on each side parallel to the ends, one shoulder extending inwardly from the side edge of the upper portion to a short intermediate edge and the other shoulder extending inwardly from the intermediate edge to the side edge of the lower portion, and the lower portion having notches cut near its extremity to form tabs of a height equal to the perpendicular distance between the parallel shoulders of each pair thereof.

3. A flexible roofing shingle having parallel ends and parallel sides, the upper portion which is substantially one half the length of the shingle being wider than the lower portion, and defined therefrom by a pair of shoulders on each side parallel to the ends, one shoulder extending inwardly from the side edge of the upper portion to a short intermediate edge and the other shoulder extending inwardly from the intermediate edge to the side edge of the lower portion, and the lower portion having notches cut near its extremity to form tabs laterally extending a distance equal to the perpendicular distance between the side edges of the upper and the lower portions and of a height equal to the perpendicular distance between the parallel shoulders of each pair thereof.

4. A flexible roofing shingle having parallel ends and parallel sides, one portion, which

is substantially one half the length of the shingle, being wider than the other portion, and defined therefrom by a double shoulder on each side, the narrower portion having notches cut therein on both sides near its extremity, and said narrower portion being underfolded near its extremity.

5. A flexible roofing shingle having parallel ends and parallel sides, one portion which is substantially one half the length of the shingle, being wider than the other portion and defined therefrom by a double shoulder on each side, the narrower portion having notches cut therein on both sides near its extremity to form two laterally extending tabs, and said narrower portion being underfolded on a transverse line in alignment with the upper edge of said tabs.

6. A roof comprising interlocked shingles, each shingle having parallel ends and parallel sides, one portion, which is substantially one half the length of the shingle being wider than the other portion and defined therefrom by a double shoulder on each side, the narrower portion having tabs extending laterally near the extremity thereof and adapted to engage with one of the shoulders of similar laterally adjacent shingles of the lower course.

7. A roof comprising interlocked shingles, each shingle having parallel ends and parallel sides, one portion of which is substantially one half the length of the shingle being wider than the other portion and is defined therefrom by a pair of spaced shoulders on each side, the other portion having notches cut near the extremity thereof to form laterally extending tabs, said portion being underfolded on a transverse line near its extremity so that doubled thickness tabs are formed thereby adapted to engage either one of the shoulders of laterally adjacent shingles of a lower course.

8. A roof comprising interlocked shingles, each shingle having parallel ends and parallel sides, one portion which is substantially one half the length of the shingle being wider than the other portion and defined therefrom by a double shoulder on each side, the narrower portion having notches cut near the extremity thereof, said narrower portion being underfolded on the transverse line joining said notches, said notches engaging the shoulders of laterally adjacent shingles of a lower course.

In testimony whereof I have affixed my signature.

WILLIAM A. HARRIS.
